UNITED STATES PATENT OFFICE.

ADAM KRYSTYNIAK, OF GREENSBURG, PENNSYLVANIA.

CIGAR-HOLDER.

1,209,596.

Specification of Letters Patent. Patented Dec. 19, 1916.

Application filed February 7, 1916. Serial No. 76,735.

To all whom it may concern:

Be it known that I, ADAM KRYSTYNIAK, a citizen of Poland, residing at Greensburg, in the county of Westmoreland and State 5 of Pennsylvania, have invented new and useful Improvements in Cigar-Holders, of which the following is a specification.

This invention relates to a cigar holder of the type provided with a needle projectable through one end of the holder for insertion in the end of a cigar to be inserted in the holder.

The primary object of the invention is to provide a cigar holder of the class described 15 having interposed between the ends thereof a casing formed from absorbent material and collapsible to permit a needle arranged within the holder to be projected beyond one end of the holder for insertion within 20 a cigar to be inserted within the holder.

A further object of the invention is to provide a cigar holder in which a cigar receiving member movable along a piercing element arranged in the holder is connected 25 with a collapsible casing in such a manner that when movement in one direction is imparted to the cigar receiving member the casing may be partially collapsed to cause the piercing element to extend beyond the 30 cigar receiving member.

A still further object of the invention is to provide a cigar holder in which a collapsible casing formed from absorbent material is interposed between the ends of the 35 holder so that when the said casing is partially collapsed the smoke from the cigar inserted in the holder will be retarded in its passage through the holder to permit the smoke to cool, and also to enable the casing 40 to absorb the tobacco tar contained in the smoke.

A still further object of the invention is to provide a cigar holder of the class described having a spring arranged within 45 the collapsible casing of absorbent material and bearing against the mouth piece and cigar receiving member of the holder to normally hold the collapsible casing in extended position, said spring also serving 50 when the casing is partially collapsed to prevent the inner peripheral surface thereof from contacting and closing the smoke passage through the holder.

With these and other objects in view the 55 invention resides in the novel combination and arrangement of parts which will be

hereinafter described and more particularly pointed out in the appended claims.

The preferred embodiment of the invention has been illustrated in the accompanying drawing, although no restriction is necessarily made to the precise details of construction herein shown, as changes, alterations and modifications in the scope of the appended claims may be resorted to when so desired.

Like characters of reference denote corresponding parts throughout the several views in the drawing in which—

Figure 1 is a side elevation of a cigar 70 holder constructed in accordance with the invention and showing a cigar inserted therein. Fig. 2 is a view similar to Fig. 1 showing the holder with the cigar removed therefrom. Fig. 3 is a horizontal longitudinal sectional view taken on the line 3—3 of Fig. 1. Fig. 4 is a vertical longitudinal sectional view through Fig. 1. Fig. 5 is a section on the line 5—5 of Fig. 4.

Referring now to the drawings in detail the numeral 1 indicates the mouth piece of the improved cigar holder which is formed of any suitable material and has extending longitudinally thereof for a portion of its length a smoke passage 2 and communicating with said smoke passage and arranged concentrically thereabout are smaller smoke passages 3. The mouth piece 1 is cylindrical in contour and tapering for a portion of its length, as indicated by the 90 numeral 4 while the remaining portion of the mouth piece is reduced and flattened to provide lip and teeth engaging surfaces 5. Extending centrally from the smaller end of the mouth piece 1 and in axial alignment 95 with the smoke passage 2 is a piercing element 6. Secured to the cylindrical portion 4 of the mouth piece 1 in any suitable manner in one end of a tapering and tubular casing 7 formed from any suitable flexible 100 absorbent material and arranged to surround in spaced relation the piercing element 6 for the greater portion of its length. Secured to the smaller end of the casing 7 and mounted to slide upon the piercing element 6 is a cigar receiving member 8, said member having extending longitudinally thereof concentrically arranged smoke passages 9 communicating at one end thereof with a flared recess 10 to receive one end 110 of the cigar when inserted in the holder. Extending longitudinally of the piercing ele-

ment 6 and wound spirally about the same is a coil spring 11, said spring having its respective terminals connected with the mouth piece 1 and the receiving member 8 for a purpose which will be hereinafter described.

When it is desired to use the cigar holder the receiving member 8 is moved along the piercing element 6 in the direction of the 10 mouth piece against the action of the spring 11, such movement of the receiving member causes the end of the piercing element to project beyond the same and also causes the casing 7 to be partially collapsed. The end 15 of the piercing element is now inserted within the end of the cigar and the cigar moved along the piercing element until the end thereof is positioned within the recess 10 thereby connecting the cigar with the holder. 20 The cigar may now be lighted and it will be noted with reference to Fig. 3 in the drawing that as the smoke is drawn through the casing 7 as indicated by the arrows the smoke will contact with the convoluted portions of the casing which retard the smoke 25 in its passage through the casing for a sufficient length of time to enable the collapsible casing to absorb from the smoke a large percentage of the tobacco tar intermingled 30 therewith. It will also be noted that when the casing 7 is partially collapsed the numerous convolutions throughout its length serve as heat radiating surfaces to enable the smoke in its passage through the casing 35 to become thoroughly cooled and that the spring 11 has not sufficient strength to press the cigar receiving member 8 against the end of the cigar with sufficient force to remove the same from the end of the piercing 40 element 6.

When it is desired to remove the cigar from the holder the cigar receiving member 8 may be manually moved along the piercing element 6 in a direction away from the 45 mouth piece 1, such movement causing the end of the piercing element to be withdrawn from the butt of the cigar and within the cigar receiving member 8 at which time the casing 7 will be fully extended and held 50 in such position by the spring 11.

By winding the convolutions of the spring 11 spirally about the piercing element 6 and in spaced relation therewith the entire collapse of the casing 7 is prevented and the 55 inner peripheral surface thereof prevented from contacting and closing the smoke passage through the holder.

From the foregoing statement taken in connection with the accompanying drawing 60 it will be at once apparent that a cigar holder has been provided, which is simple in construction, inexpensive of manufacture and highly efficient in use.

Having thus described the invention what is claimed as new is:—

1. A cigar holder comprising a mouth piece, a piercing element connected with the mouth piece, a receiving member carried by the piercing element, and a flexible casing formed from absorbent material and interposed between the mouth piece and receiving member.

2. A cigar holder comprising a mouth piece, a piercing element extending from the mouth piece, a receiving member mounted upon the piercing element distant from the mouth piece, and a flexible casing formed from absorbent material terminally connected with the mouth piece and receiving member, said casing being collapsible.

3. A cigar holder comprising a mouth piece, a piercing element extending centrally therefrom, a collapsible casing formed from absorbent material and having one end connected with the mouth piece, and a receiving element connected with the other end of the casing and mounted to slide upon the piercing element to collapse or extend said casing.

4. A cigar holder comprising a mouth piece, a piercing element extending centrally therefrom, a collapsible casing formed from absorbent material surrounding the piercing element and spaced therefrom, said casing being tapered and having its larger end secured to the mouth piece, a receiving element connected with the other end of the casing and mounted to slide on the piercing element to collapse said casing, and a spring interposed between the mouth piece and the receiving member to normally hold the casing in extended position.

5. A cigar holder comprising a mouth piece, a piercing element extending centrally therefrom, a collapsible casing formed from absorbent material surrounding the piercing element and spaced therefrom, said casing being tapered and having its larger end secured to the mouth piece, a receiving element connected with the other end of the casing and slidably mounted on the piercing element, and a coil spring interposed between the mouth piece and the receiving member, said spring having the convolutions thereof wound spirally about the piercing element in spaced relation thereto and adapted to prevent contact of the inner peripheral surface of said casing when collapsed.

In testimony whereof I affix my signature 120 in presence of two witnesses.

ADAM KRYSTYNIAK.
